UNITED STATES PATENT OFFICE.

MARY A. FERGUSON, OF INDIANAPOLIS, INDIANA.

DRESS-MAKER'S CHART.

SPECIFICATION forming part of Letters Patent No. 269,652, dated December 26, 1882.

Application filed July 24, 1882. (No model.)

To all whom it may concern:

Be it known that I, MARY A. FERGUSON, a citizen of the United States of America, residing at Indianapolis, in the county of Marion and State of Indiana, have invented certain new and useful Improvements in Dress-Makers' Charts, of which the following is a specification, reference being had therein to the accompanying drawings.

10 My invention relates to certain improvements in scales or rules for making patterns for garments; and it consists in certain features hereinafter described, and specifically set forth in the claim.

15 Figures 1 and 2 illustrate opposite sides of a scale constructed in accordance with my invention.

The scale may be made of any suitable material, and the indicating lines and figures may 20 be printed or otherwise impressed thereon, and its outlines consist essentially of one straight edge (the left of Fig. 1 and the right of Fig. 2) terminating in a substantial semicircular curve at one end and in a less curve at the 25 other, and the opposite edge being slightly convex, and so curved as to produce a wedge shape at one end and a projecting curved point at the other end, as clearly shown in the drawings. Thus the semicircular end is wider than 30 the body portion, and the opposite end is narrower, and each is joined to the same by curved lines. The outline described has certain functions hereinafter described. Upon one side of the scale is printed or otherwise 35 impressed a double marginal line (or lines) parallel to the edge of the scale, and therefore in contour agreeing with the shape of the scale. These lines are subdivided into spaces (inches and fractions thereof) on the side K from the 40 point to 8, and from the opposite end, where the side merges into the semicircle, from 1 to 46, the subdivisions in each scale growing gradually less in length as they approach the highest number in the series, with the exception that 45 the space 5 is about one and one-quarter inch long, and the following space (of an inch) being numbered 18, 19, 20, 21, and 22 by quarters. On the opposite edge the variation occurs at the 3 space, the next being 18, 19, &c., 50 by quarters, up to 48, and five inches from the 48 space the spaces are numbered from 18 back-

ward, by half-inch spaces, to 12, toward the short or inside curve. There is also on this side of the scale a table showing the order of measurements, as "1 neck," "2 shoulder," "3 55 breast," up to "9 across the back," as herein-after described. On the opposite side similar marginal lines and spaces are provided for front-arm, front-shoulder, back-arm, and dart measurements, as indicated, and a line of perforations, 12, as usual in this class of devices.

This being the construction, the method of using the scale is as follows: Measurements are taken with a tape-line in the order indicated, the lengths being given herein in brackets and indicating inches: first, the neck, [14;] second, length of shoulder-seam, [6½;] third, breast, [8;] commencing two inches from center of back of neck, over shoulder, straight down in front; fourth, bust, [12;] from center 70 to side seam; fifth, arm, (around,) [14;] sixth, length of waist, [8½;] seventh, around waist, [28;] eighth, down back, [8;] ninth, across back, [7;] from center to side seam. Following these measurements and striking or laying 75 off a perpendicular line on the paper from which the pattern is to be made, place the point A, Fig. 2, thereon, and the short curve up to 14 will give the outline of that portion of the neck. A curved line of 6½ on the wedge 80 end will give the shoulder-seam. Turn the scale over and use the long curve to 14, and it will give the outline of the armhole—that is, so much thereof as is comprised within the front half of the pattern, which is now being 85 laid out.

In the operation thus far, governed by the measurements above given, the several outlines have been obtained by using the following portions of the scale: the neck from A to B, Fig. 90 2; the shoulder from C to D, Fig. 1, and the armhole from G to H, same figure. The remaining outlines are produced by the following portions: in Fig. 1, from C to E, breast; from C to F, bust; from C to I, length of waist at 95 side seam. In Fig. 2, from J to K, front waist-length. In Fig. 1, from L to M, height of dart; from N to N' is dart-width, and from N to C and N' to C gives the outlines of dart; from C to O, side seam of back; O to P, cross-seam 100 of waist and back; C to L, back (line of) shoulder-seam; R to S, armhole on back-pattern;

from U to V, Fig. 2, back-waist line; from C to W, Fig. 1, hip; from X to Y, darts below waist. The line of perforations at 5, Fig. 1, may be used to outline patterns for children's garments—that is, the front armhole, as indicated. In this manner, by starting at a given straight line and guided by the measurements, the outlines and directions are determined, when all that remains is to cut out the paper pattern according to the lines and apply it to the cloth as a guide in cutting the garment.

Having described my invention and its operation, what I claim as new, and desire to secure by Letters Patent, is—

15 The scale herein shown and described, consisting of a blank of suitable material having the wedge-shape point and semicircular end, the projecting curved point, a straight side,

and an opposite slightly-convex side, and bearing parallel marginal lines divided into spaces 20 regularly and proportionally diminishing from an end toward the middle of the scale-edge, and also bearing a table of the order of measurements and lines of perforations, said marginal lines or divisions bearing the names and 25 adapted in outline for the measurement of front arm, back arm, front shoulder, and dart width and rule, all substantially as shown and described.

In testimony whereof I affix my signature in 30 presence of two witnesses.

MARY A. FERGUSON.
